SANDLESS CASTING COMPANY, OF PHILADELPHIA, PENNSYLVANIA, A CORPORA-
TION OF DELAWARE.

PERMANENT METAL MOLD.

1,097,849.

Specification of Letters Patent.

Patented May 26, 1914.

Application filed October 26, 1910. Serial No. 589,119.

To all whom it may concern:

Be it known that I, EDGAR A. CUSTER, a citizen of the United States, residing at Philadelphia, in the State of Pennsylvania, have invented certain new and useful Improvements in Permanent Metal Molds, of which the following is a specification, reference being had to the accompanying drawings forming a part thereof.

10 The object of this invention is to provide means in a permanent metal mold whereby injury to the mold caused by the molten metal as it enters the matrix through the gate may be avoided.

15 A further object of the invention is to provide means whereby the dimensions of the gate may be varied without reconstructing the mold.

20 The various other objects of the invention will be more fully set forth in the following description of one form of permanent mold embodying my invention, which consists in the new and novel features of construction and combinations of parts hereinafter set forth and claimed.

25 In the accompanying drawings: Figure 1 is a side elevation of a section of a metal mold embodying my invention. Fig. 2 is a plan view of the same in section.

30 Referring to the drawings, which show one form of a mold embodying my invention, the mold comprises two parts or sections *a* which are hinged together as at *b*. Preferably the meeting face of each section 35 of the mold is suitably recessed as at *c* to receive an insert *d*. Both the mold and the inserts are recessed or channeled to form the sprue *e*, the gate *f* and the matrix *g*. Preferably a part of the sprue and all of the 40 gate are formed in the inserts, which may be of sufficient length to form a part of the wall of the matrix as at *h*. The casting *i* may be poured around the removable cores *j* which are inserted within the matrix.

45 One or more channels *k* may be provided in the insert, which communicate with a supply pipe *l* having a suitable valve *m* therein, so that water or other cooling fluid may be caused to flow through the insert in order to control the temperature thereof and to prevent the insert from becoming heated above any desired maximum temperature

through contact with the molten metal passing through the gate, and also to cause the metal of the casting contiguous to the gate 55 to set simultaneously with the metal in the other parts of the casting.

The insert may be of any suitable material. In practice, the insert may be made of a different metal than the body of the mold 60 for the purpose of either promoting or retarding the radiation of heat, or it may be made of some different material such as a combination of fuller's earth with talc or lava rock which will be able to withstand 65 the harmful effects of the molten metal.

Heretofore much damage has been caused by the cracking of permanent molds at or near the gate, which resulted in the practical destruction of the mold itself, since the 70 cracks so formed could not be removed or repaired. By means of this construction the parts of the mold most subject to injury can be readily removed and a new insert put in place. Furthermore it is obvious that 75 the size of the sprue and of the gate may be changed by substituting inserts having different sized channels or recesses formed therein.

I claim as my invention:

1. In a permanent metal mold comprising sections, an insert detachably secured to one of the sections and adapted to contact with the molten metal supplied to the mold, said insert forming part of the face of said section and being formed of different material than the section.

2. In a permanent metal mold comprising sections, the combination with each section, of an insert detachably secured to said section and adapted to contact with the molten metal supplied to the mold, each insert being formed of different material than the sections and each having a portion of the sprue and the entire gate formed therein.

3. In a permanent metal mold comprising sections the combination with each section, of an insert secured to said section and adapted to contact with the molten metal supplied to the mold, each insert having 100 channels formed therein for the passage of a liquid and forming part of the wall of the sprue and the matrix.

4. In a permanent mold comprising sec-

tions, the combination with each section, of
an insert secured to said section and being
channeled to form a portion of the gate and
having a passage therethrough adjacent to
5 said gate, and means for supplying liquid to
said passage, said inserts being adapted to
register with each other.

This specification signed and witnessed
this 15th day of October A. D., 1910.

EDGAR A. CUSTER.
